Response filed Oct. 6, 2015 to Notice of Non-Compliant Amendment for U.S. Appl. No. 13/698,417.

(Continued)

Primary Examiner — Robin V Webster(74) *Attorney, Agent, or Firm* — Paul D. Bianco; Fleit Gibbons Gutman Bongini & Bianco PL(57) **CLAIM**

The ornamental design for a paint spray gun with pattern, as shown and described.

DESCRIPTION

FIG. 1 is a first side view of a paint spray gun with pattern according to the present invention;

FIG. 2 is second side view of the paint spray gun with pattern of FIG. 1;

FIG. 3 is a front view of the paint spray gun with pattern of FIG. 1; and,

FIG. 4 is a back view of the paint spray gun with pattern of FIG. 1.

The features shown in broken line are for illustrative purposes only and form no part of the claimed invention.
